UNITED STATES PATENT OFFICE.

HIRAM H. SPONENBURG, OF GURNEE, ILLINOIS, ASSIGNOR, BY MESNE ASSIGNMENTS,
TO OTTO R. BARNETT, OF CHICAGO, ILLINOIS.

RAIL-ANCHOR.

1,357,360.

Specification of Letters Patent.

Patented Nov. 2, 1920.

Application filed October 3, 1919. Serial No. 328,253.

To all whom it may concern:

Be it known that I, HIRAM H. SPONENBURG, a citizen of the United States, residing at Gurnee, in the county of Cook and 5 State of Illinois, have invented certain new and useful Improvements in Rail-Anchors, of which the following is a specification.

My invention relates to rail anchors for resisting the tendency of railroad rails to move longitudinally and has for its principal object to provide a novel form of anti-creeping device which may be readily applied to rails, the base flanges of which vary 10 in width or thickness, which when in operative position will maintain its initial grip on the rail with spring pressure so that it will not be displaced or loosened by the vibration of the rail or other disturbing influence, and which will take a biting hold 15 on the rail base during a creeping action of the rail.

The above objects are obtained by making an anchor device with jaws, the distance between which is normally less than the width 20 of the rail base to which the device is intended to be applied, and forming the device with a bend which will yield to permit the jaws to be engaged with opposite edges of the rail base.

30 The invention also contemplates a device formed with a spring jaw which will yield to facilitate the application of the device to the rail and which will bear with spring pressure against the upper and lower surfaces of the rail base.

The preferred form of my invention is illustrated in the accompanying drawings wherein:

Figure 1 is a plan view of a railroad rail 40 showing a rail anchor device constructed in accordance with my invention applied to the base flange thereof, a portion of the anchor device being broken away so as to illustrate the manner in which the device 45 takes a biting hold on the rail base during the presence of a creeping action of the rail.

Fig. 2 is a front view of the device shown in Fig. 1, and illustrating in dotted lines 50 one of the positions which the anchor device assumes while the same is being applied to the base flange of a rail.

Fig. 3 is a view in perspective of the anchor device shown in the preceding figures; 55 and

Fig. 4 is a view in perspective of a portion of a railroad rail showing my preferred form of anchor device applied thereto in operative position.

Like characters of reference designate 60 like parts in the several figures of the drawings.

The rail anchor device illustrated in the drawings is preferably made from a flat piece of spring metal bent to form jaw portions 10, 11, which engage opposite edges of the base flange of a railroad rail 12, and is provided with a downwardly extending portion 13 which abuts against one of the vertical faces of a cross-tie 14. The jaw 65 portion 10 is formed by bending one end of the metal blank upwardly to form an irregular loop having its outer face formed with reverse curves 15, 16 and 17. The inner face 18 of this loop is substantially vertical 70 and is slit as indicated at 19-20 and the edges bent outwardly to form lips 22-23 which engage with the upper surface of the rail base. The portion of the metal blank intervening between said lips extends downwardly to provide a spring tongue 21 which 75 engages the vertical edge of the rail base. The lips 22, 23, being of spring metal will yield when the jaw 10 is forced on the rail base and bear with spring pressure against 80 the inclined surface thereof, the resiliency of these lips in addition to holding the body portion of the anchor in frictional contact with the bottom surface of the rail base so as to maintain a tight initial grip of the 85 jaw on the rail, will also flex sufficiently to permit the application of the device to rails having base flanges which vary in thickness or contour.

The body portion 24 is preferably offset, as shown at 25 to permit the tongue 21 to extend below the lower edge of the rail; the lower edge of the tongue being, preferably, bent inwardly, as indicated at 25a so as to extend a short distance under the base flange. The other end of the blank 95 100 is bent upwardly, as indicated at 26 to form the jaw 11, which engages the opposite edge of the rail base. This end of the anchor terminates in an outwardly projecting bend forming a loop 27. This loop facilitates the 105 application of the device to the rail by providing a curved surface 28 adjacent the jaw portion 11 adapted to ride over the lower edge of the rail base when the device is being applied, and also provides a suitable hooked 110

portion through which a crow-bar 29 or other suitable element may be inserted to enable the workmen to strain the bent portions of the device sufficiently to permit the 5 edge 30 of the jaw 11 to clear the rail when the device is being applied. The tie-abutting flange 13 of the device is arranged adjacent one end of the device, preferably adjacent the jaw 10 and the other end is made 10 somewhat narrower than that of jaw 10, so that the jaw 11 will normally stand a short distance away from the tie. The tie-abutting 15 flange 13 being formed at one end of the anchor will permit a slight skewing action of the device when the rail tends to creep toward the tie, and in this way tension the device to increase the grip of the device on the rail base. The lip 21 of the jaw 10 and the vertical portion 26 of the jaw 11 are 20 formed with sharp edges 31, 32, which are adapted to take a biting hold on the vertical edges of the rail during the said creeping action so as to prevent any appreciable relative movement between the rail and the anchor device. If desired the sharp edges may be embedded into the edge of the rail when the device is being applied by striking the portion on which these edges are formed so as to drive the sharp edges into the rail. 25

30 The device is applied to the rail by inserting the jaw portion 10 over one edge of the rail base until the vertical edges of the rail and the tongue 21 are in engagement. When the anchor is thus far applied it assumes the position illustrated in dotted lines 35 in Fig. 2. A crow-bar or some suitable device is then inserted through the hook portion of the jaw 11 and the anchor sprung in the direction indicated by the arrow in Fig. 2 40 until the edge 30 of the jaw 11 clears the edge of the rail, as shown in full lines in the drawing. The rear edge of the portion 26 of jaw 11 and the forward edge of the tongue 21 of the jaw 10 may then be tapped 45 with a hammer or some suitable device to embed the sharp edges 31, 32 in the vertical edge of the rail.

I claim:

1. A rail anchor comprising a rail base 50 embracing member formed with jaws which engage opposite edges of a rail base, said jaws being adapted to yield to compensate for variations in the width or contour of the base flanges of rails to which the anchor is applied. 55

2. A rail anchor comprising a rail base embracing member formed with jaws which engage opposite edges of a rail base, said jaws being adapted to yield to permit the 60 application of the anchor to a rail and to compensate for variations in the width or contour of the base flanges of rails to which the anchor is applied.

3. A rail anchor comprising a rail base 65 embracing member formed at one end with

a jaw which engages one edge of the rail base and at the other end with a loop providing a jaw which engages the opposite edge of said base; said loop being adapted to yield to permit the application of the first 70 mentioned jaw to the rail and being formed with resilient members which engage the inclined surface of said base flange and are adapted to yield vertically.

4. A rail anchor comprising a rail base 75 embracing member formed at one end with a jaw which engages one edge of the rail base and at the other end with a loop providing a jaw which engages the opposite edge of said base; said loop being adapted 80 to yield to permit the application of the first mentioned jaw to its operative position and to yield vertically so as to resiliently engage the upper and lower faces of the base flange.

5. A rail anchor comprising a rail base 85 embracing member formed at one end with a jaw which engages one edge of the rail base and at the other end with a loop providing a jaw which engages the opposite edge of said base; said loop being adapted 90 to yield to permit the application of the device to rails having base flanges of various widths and being formed with vertically yieldable members which engage the inclined surface of said base flange. 95

6. A rail anchor comprising a rail base embracing member having a tie abutting flange and formed at one end with a jaw which engages one edge of the rail base and at the other end with a loop providing a jaw 100 which engages the opposite edge of said base; said loop being adapted to yield to permit the application of the device to rails having base flanges of various widths and being formed with vertically yieldable members which engage the inclined surface of said base flange. 105

7. A rail anchor comprising a rail base embracing member having jaws which engage opposite edges of the base flange of a 110 rail and provided with a tie abutment; one of said jaws being in the form of a vertically disposed loop the free end of which yields to permit the application of the device to the rail and bears with spring pressure against 115 the vertical edge of the rail base when the device is in operative position.

8. A rail anchor comprising a rail base embracing member having jaws which engage opposite edges of the base flange of a 120 rail and provided with a tie abutment; one of said jaws being in the form of a loop the free end of which bears with spring pressure against the vertical edge and inclined surface of the rail base and being adapted to 125 yield to permit the application of the other jaw to the rail.

9. A rail anchor comprising a rail base embracing member having jaws which engage opposite edges of the base flange of a 130

5 rail and provided with a tie abutment; one of said jaws being in the form of a loop the free end of which bears with spring pressure against the vertical edge and inclined surface of the rail base and being adapted to yield to permit the application of the anchor to rails having base flanges of different widths and thickness.

10 10. A rail anchor comprising a rail base embracing member having jaws which engage opposite edges of the base flange of a rail; one of said jaws being in the form of a loop the free end of which is slit and the edges thereof bent to engage the upper surface of the base flange at points longitudinally remote from each other.

15 11. A rail anchor comprising a rail base embracing member having jaws which engage opposite edges of the base flange of a rail; one of said jaws being in the form of a loop the free end of which is slit and the edges thereof bent to provide resilient elements which engage the upper surface of the base flange.

20 25 12. A rail anchor comprising a rail base embracing member having jaws which engage opposite edges of the base flange of a rail—one of said jaws being in the form of a loop the free end of which is slit and the edges thereof bent to provide resilient elements which engage the upper surface of the base flange and the portion intervening between the said slits providing a spring tongue which engages the vertical edge of the rail base.

30 40 13. A rail anchor comprising a rail base embracing member having a jaw which fits over one edge of the rail base and with a jaw which fits over the opposite edge of said base; the first mentioned jaw being adapted to be strained to permit the second mentioned jaw to be operatively engaged with the rail base.

45 50 14. A rail anchor comprising a rail base embracing member having a jaw which fits over one edge of the rail base and with a jaw which fits over the opposite edge of said base; the first mentioned jaw being adapted to be strained to permit the second mentioned jaw to be operatively engaged with the rail base and the said last mentioned jaw being provided with an outwardly curved tongue which rides over the edge of the rail base when the anchor is applied.

55 15. A rail anchor comprising a rail base

embracing member having a jaw which fits over one edge of the rail base and with a jaw which fits over the opposite edge of said base; the first mentioned jaw being adapted to be strained to permit the second mentioned jaw to be operatively engaged with the rail base and the said last mentioned jaw being provided with an outwardly curved tongue providing a cam surface which rides over the edge of the rail base when the anchor is applied.

60 65 16. A rail anchor comprising a rail base embracing member having a jaw of a substantially loop shape which fits over one edge of the rail base and with a jaw which fits over the opposite edge of said base; the first mentioned jaw being adapted to be strained to permit the second mentioned jaw to be operatively engaged with the rail base.

70 75 17. A rail anchor comprising a rail base embracing member having jaws which fit over opposite edges of the base flange of a rail one of said jaws being of substantially loop-shape having a plurality of reverse bends and being adapted to yield to permit the application of the other jaw to its operative position.

80 85 18. A rail anchor comprising a rail base embracing member having a tie abutment, jaws which fit over opposite edges of the base flange of a rail one of said jaws being of substantially loop-shape having a plurality of reverse bends and being adapted to yield to permit the application of the other jaw to its operative position.

90 95 19. A rail anchor comprising a rail base embracing member having jaws which engage with opposite edges of the rail base and having sharp edges adapted to be embedded in the vertical edge of said base to increase its hold thereon; one of said jaws being of substantially loop-shape and being adapted to yield to permit the other jaw to be applied to its operative position.

100 105 20. A one piece anchor made from a flat piece of spring metal bent to provide jaws which engage with opposite edges of the rail base and having sharp edges adapted to be embedded in the vertical edge of said base to increase its hold thereon; one of said jaws being of substantially loop-shape and being adapted to yield to permit the other jaw to be applied to its operative position.

HIRAM H. SPONENBURG.
